[57] CLAIM

The ornamental design for a combined headband and radio, as shown and described.

DESCRIPTION

FIG. 1 is a side elevational view of a combined headband and radio showing my new design on a wearer shown in broken lines;

FIG. 2 is a top plan view thereof;

FIG. 3 is a side elevational view thereof;

FIG. 4 is a bottom plan view thereof;

FIG. 5 is an elevational view of the side opposite that shown in FIG. 3;

FIG. 6 is a front elevational view; and

FIG. 7 is a rear elevational view thereof.
